UNITED STATES PATENT OFFICE

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA

WIRED BROADCAST DISTRIBUTING SYSTEM

Application filed November 27, 1926. Serial No. 151,116.

My invention relates to broadcast distribution, and is a continuation in part of my copending application, Serial No. 746,357, filed October 28, 1924, for an organized system of radio broadcast distribution. The present invention pertains especially to broadcast distribution over wires or wire networks by carrier current and in general parallels in wired distribution the radio distribution method and system of the earlier application, and provides further developments relating to wired broadcast distribution.

It has for its objects to provide predetermined selective distribution through and to different points over conductors common to several paths or routes of distribution, to provide predetermined distribution with selection at the receiving point, to provide distribution of the same signals to different geographical time divisions at different periods of ultimate time to compensate for differences in geographical time, to provide broadcast distribution to subscribers in groups connected to the same or different wire networks through different subscribers' service stations individual to a group and to utilize the wire networks and trunking connections of existing wired electrical distributing systems and communication systems. Other objects of the invention will be apparent from a perusal of the following specification and the drawings accompanying the same.

In the drawings:

Fig. 1 is a diagram of an area such as that of the United States divided into clock time divisions showing the distribution of the different classes of stations and their physical or trunking connections.

Fig. 2 is a more detailed diagram of one of the main branches of the distribution channels and sub-branches thereof between the main station and a subscriber's station.

Fig. 3 is a circuit diagram of a subscriber's receiving set.

Fig. 4 is a schematic diagram showing a mixed system of wire and radio distribution and sub-distribution.

Fig. 5 is a diagram of a modified arrange-

ment for effecting selective distribution or routing by use of different sending frequencies.

Fig. 6 is a diagram showing the master B stations or time division stations connected with the master or primary station through individual trunks and the relation of the succeeding orders of stations to the B stations.

Fig. 7 is a diagram illustrating an arrangement for effecting predetermined distribution or routing by forward frequencies.

Fig. 8 illustrates a modification of the arrangement of Fig. 7 in which selective distribution may be effected among different groups of subscribers on a common network.

Fig. 9 is a diagram illustrating the method of distributing to subscribers' stations through relay stations on a common wired network.

Fig. 10 is a table or chart showing the time schedule and order of repetition of different classes of items throughout the system.

In Fig. 1 is shown the order or classification of the different relaying and distributing stations in stages expanding outwardly from a primary or master station to the ultimate receiving stations of subscribers. The area throughout which the stations are distributed is here shown as that of the United States with the divisions between its time zones or sections indicated by heavy dividing lines. The primary or master station for the whole system is designated the A station which is indicated at A in the eastern time division.

The next order of stations are the B stations, indicated in the drawings by the letter B, and of which there are several in each time division. Of the several B stations in a time division one is a leading or head station for the division which is termed the master B station. The master B stations for the eastern, central, mountain and Pacific time divisions are indicated at B¹, B², B³, and B⁴ respectively while the sub B stations are similarly designated with the addition of

a subscript, for example the sub B stations under master station B³ are indicated B₃¹, B₃², etc. A common or main trunk line MT connects all the master B stations with the

area indicated at A. The next order of stations are the C stations, indicated in the drawings by the letter C, and of which there are several in each time division. The C stations are connected to the B stations by trunk lines, indicated in the drawings by the letter T, and the C stations are connected to the A station by trunk lines, indicated in the drawings by the letter M.

The B stations are connected to the C stations by trunk lines, indicated in the drawings by the letter S, and the C stations are connected to the A station by trunk lines, indicated in the drawings by the letter L. The B stations are connected to the A station by trunk lines, indicated in the drawings by the letter K, and the C stations are connected to the A station by trunk lines, indicated in the drawings by the letter J.

primary or A station. Each sub B station connects with this main trunk at its respective master B station, for example B_1^3 , or another sub B station between it and the master B station for example B_4^2 . The next order of stations are the local distributing or C stations, indicated at C^1 , C^2 , etc. which receive from the B stations and distribute to the ultimate receiving stations or subscribers' stations D, indicated at D.

To afford selective distribution or routing of broadcast items from the A station to the different time divisions, the B stations of the different time divisions are tuned to receive on different carrier current frequencies respectively. Thus the A station sends to the B^2 stations on frequency FX, to B^3 stations on frequency FY, etc.

For a more detailed disclosure of the connections and system of distribution from the B stations on to the subscribers' station or D stations reference is to be had to Fig. 2 in which the connections from the master B station B^3 , C^2 and its subscribers' stations D (of Fig. 1) are elaborated. In Fig. 2, the portion above the bracket marked B^3 is situated at the B station B^3 while that above the bracket marked C^2 is situated at the station C^2 except the portion marked D which is a subscriber's or D station. The "power station" indicated at the extreme right is a power station whose network is used as the transmission medium between the subscriber's local distributing station C^2 and the subscribers' stations D, and which power station may be located with or at a distance from the station C^2 .

Referring to Fig. 2 more in detail MT is the main or common trunk leading from the A station through or past the station B^3 onto the next B station B^4 or to a sub B station such as B_2^3 , (Fig. 1). To compensate for or off-set attenuation in the main trunk or branches thereof, band repeaters may be inserted as indicated by the rectangle labeled "Band Rep." situated, preferably, at the master B stations. At the station B^3 the branch trunk 1, connects with the main trunk MT and extends this connection through multiple taps 2, 3, etc. to the input side of carrier current frequency filters 6, 7, etc. tuned to pass one only of the four frequencies assigned to the four master B stations which frequencies are designated FW, FX, FY and FZ for the stations B^1 , B^2 , B^3 and B^4 respectively. Normally each B station takes from the main trunk only the frequency assigned to it. For example at station B^3 (Fig. 2) only the filter 8 for frequency FY is connected through its closed switch 12 to the branch 1 leading from the main trunk MT, the remaining filters being disconnected therefrom at their open switches 10, 11 and 13. While this is the normal situation, especially where all the B stations are connected

to the A station through a common trunk, any of the other filters may be switched onto the trunk to take one or more of the items on the other frequencies FW, FX or FZ, where occasion requires. The use of several filters at the same time to take several items from the A station at the same time is the normal situation where separate trunks are used to connect the different master B stations with the A station, as shown in Fig. 6, a modification to be later described in detail.

For each of the relay filters 6, 7, etc. there is a corresponding local transmitter 16, 17, 18 and 119 each comprising an oscillator, modulator and transmitting filter as diagrammatically indicated. The transmitters 16, 17, etc. are designed to transmit on the standard carrier current frequencies FW, FX, etc. so that whatever one or more of these frequencies are not being taken from the A station may be used for items originating at the master B station. The output circuits of the relay filters and the transmitters terminate in multiple jacks 14-15, 19-20, etc. which enable them to be connected in various combinations through plugs 33, 34, etc. and coupling amplifiers 41, 45, etc. to the distributing lines or trunks 49 and 50, leading to the C stations C^1 and C^2 served by the station B^3 . The coupler amplifiers 41, 45, etc. may be of any known or other form of one way amplifier, as indicated by the arrows, preferably of the usual audion tube type, so that when two trunks such as 49 and 50 are connected to the same source through these amplifiers there will be no cross connection between the trunks.

At the C stations, for example C^2 , a set of filter couplers 52, 53, etc., and local transmitters 62, 63, etc., are provided for the different standard carrier current frequencies FW, FX, etc., the relay filters being associated with the trunk 50 in the same manner as are those of the B station with its incoming trunk. The output circuits of the relay filters and transmitters terminate in jacks 60-61, 66-67, etc., through which they may be connected in various combinations through plugs 72, 73, etc. and coupling, one-way amplifiers 76, 77, etc. to the network 80 served by the subscriber's distributing station C^2 , to which the ultimate receiving stations or subscribers' stations D are connected. This network is here shown as that of an electric power distributing circuit of a power station 81 but may be any other electrical network or one provided for the purpose. While the subscriber's house circuit 82 is here shown directly connected through the lead in wires 83 to the main power line or network for the sake of clearness and simplicity of disclosure, it is to be understood that such connection may be and preferably is made through protective devices, transformer, house meter, etc. An ordinary attachment

plug 84 is used for connecting the subscriber's receiving set R to the house circuit, the receiving set being preferably self contained as indicated and including suitable protective devices such as blocking condensers and the like not shown in Fig. 2. As with the B station, the relay filter 54 for the frequency FY is the only one normally connected to the branch trunk 51, so that the frequency FY assigned to its B station will be relayed onto its subscribers, the other relay filters being connected with the branch trunk 51 when occasion requires as for selecting from the trunk 51 such of the frequencies FX, FY, etc. as may be put on this trunk from the station B³ or from the A station through the station B³. Where one or more other C stations are served from the same trunk or distributing line 50, this trunk is extended preferably through a band repeater to the nearest such station as indicated at 85 where the trunk is shown as extending to a sub C station C², which station is not shown in Fig. 2 but which it is to be understood is equipped similarly to the station C² for serving a group of subscribers on another network. Such of the standard frequencies FX, FY, etc. as are not being used for distribution from the station B³ through C² over the network 80 may be used for transmitting over this network items originating at C², one or more of the transmitters 62, 63, etc. being used according to the frequencies required.

In Fig. 3 is shown a detailed diagram of the circuits and apparatus elements of the subscriber's receiver R at a subscriber's station D. This consists of a detector tube 86 having its filament grid, or input circuit connected to a pair of primary input busses 87-88 arranged to be connected to the primary winding of any one of a set of four tuned couplers 89 to 92, through a pair of contacts 93 to 96 of one of the push button switches 97 to 100, respectively, each of which connections includes a grid leak and grid condenser as indicated in the conventional manner at 101. Each of the secondary windings of the tuned couplers 89 etc. is arranged to be connected across the secondary input busses 102-103 upon closure of its respective push button switch 97, etc. through the extreme right hand contact thereof, the left hand terminal of each secondary winding being permanently connected to the bus 102 while the right hand terminal is connected through the push button contact to the lower bus 103. The tuned couplers 89 to 92 are tuned to pass the frequencies FW to FZ respectively. While the connection of only one terminal of each of the primary and secondary windings of the coupler coils is shown as being controlled through the switch contact, it will be understood that the connection of both terminals may be so controlled by the use of additional contacts in the push buttons where it is desired to effect complete disconnection from the common busses of coils not being used. The primary input busses 102-103 are connected through suitable blocking condensers 104-105 to the terminals of an ordinary electric light attachment plug 84 through the engagement of which with a socket 106 wired to the house circuit 82, the connection is extended to the house circuit.

At the extreme left of each push button switch 97, 98, etc. is a normally open contact like that indicated at 107 arranged upon closure to connect the filament battery bus 108, leading from the upper terminal of the filament battery A, to the filament bus 109 which connects with one terminal of the filament through a filament rheostat 110. Thus as the other terminal of the filament connects through conductor 111 with the lower terminal of the battery A, closure of any one of the push button switches will complete the filament circuit. The plate or output circuit of the tube 86 is completed through the jack 112 by connection of the plate element of the tube with the lower jack spring, the connection of the upper jack spring with the positive terminal of the plate battery B, and the connection of the negative terminal of the plate battery through conductor 108 with the filament. The plate or output circuit may be traced from the upper terminal of battery B, upper spring of jack 112, lower spring of jack 112, plate element of tube 86, filament of tube 86, conductor 109, extreme left hand contact such as 107 of whatever switch is closed, conductor 108 back to negative terminal of battery B. It is desirable that each time one of the push button switches 97 etc. is closed, it will so remain until another is closed whereupon it will automatically release or return to the open position, and that the last button actuated may be restored at will so as to open all circuits. To this end use may be made of any known or other suitable form of a push button set of the type used in telephony for a party line ringing key set. The set of push buttons here shown is of this type and consists essentially of the set of switching buttons 97, 98, 99 and 100 with a release or off button, each button being arranged to engage with the edge of an opening such as 113 in a lock plate 114 to shift the plate laterally and catch thereunder and be held in actuated position until another button is actuated to shift the lock plate to release the first and lock itself in actuated position, the lock plate being mounted for lateral parallel movement and held normally in locking position by supporting springs 115.

In the operation of the system as shown in Figs. 1 to 3, assuming the main trunk MT to be supplied from the primary station A with different programs or items on the standard frequencies FW, FX, FY and FZ for the 100

different time divisions, eastern, central, mountain, and Pacific respectively, the master B station B³ for the mountain time division picks up the item transmitted on the carrier frequency FY through the branch trunk 1 (Fig. 2) switch 12 and relay filter 8 from which it is distributed to one or both of the trunks 49 and 50 through the multiple jacks 25 and 26, plugs 37 and 38 and amplifiers 43 and 47 respectively. The whole group of standard frequencies FZ, FY, etc. is also passed onto the next succeeding master B station B⁴ and to other sub B stations in the same time division as B³ for example B₁³ and B₂³ as indicated in Fig. 1. At the station B² (Fig. 2) any of the other frequencies not being used for the item or items received by it from the main trunk MT may be used by it for originating matter to be distributed to its C stations. For example, the transmitters 16 and 17 may be connected through their jacks 19, 20, 23, 24, plugs 33, 34, 35, 36 and amplifiers 41, 42, 45, 46 to the trunks 49 and 50 leading to the stations C¹ and C² to put thereon two other items on the standard carrier frequencies FW and FX, the transmitters 16 and 17 being arranged to transmit on these frequencies respectively.

The three items now being sent over the trunk 50 on the frequencies FW, FX and FY, are passed on through the band repeater to a sub C station of station C² as indicated where the trunk 50 is shown connected through a band repeater to an extension trunk leading to station C₁². At station C² the carrier waves of frequencies FW, FX and FY are taken off the trunk 50 through extension 51 and relay filters for these frequencies, FW, FX and FY, the switches 56, 57 and 58 being closed for this purpose, and the transmission extended through the jacks 60, 66, 68, plugs and amplifiers 72-76, 73-77, 74-78 to the network 80. As the frequency FZ is not included in this group of relayed frequencies, the stationary C² uses the remaining frequency FZ for originating a fourth item or program of items by use of the transmitter 65 which is also connected through jack 71, plug 75 and amplifier 79 to the network 80, over which all the different items on their respective frequencies are now distributed in common to the house circuits 82 of all the subscribers' stations D by way of the leading in conductors 83. At the subscriber's station D (Figs. 2 and 3), the carrier currents pass from the house circuit 82 through the plug 84 and blocking condensers 104-105 to the primary input busses 102-103. The subscriber now actuates one of the push button switches according to the item he desires, for example, if the item being transmitted on frequency FW is desired he depresses the push button 97 which when depressed releases the "off" button, closes its contacts and locks itself under

the lock plate 114. This completes the energizing circuit of the filament of the tube 86 by connecting the battery lead 108 to the bus 109, and connects the input circuit of the detector tube 86 to the primary input busses 102-103 through the tuned filter coupler 89 tuned to the frequency FW. The connection of the primary winding of the coupler across the conductors 102-103 may be traced from upper primary input bus 102, primary of filter coupler 89, right hand contact of push button 97, to bus 103, while the connection of the secondary winding to the input circuit of the tube may be traced from left hand terminal of filament, secondary input bus 87, secondary of coupler 89, middle contact 93 of push button 97, grid leak and condenser 101, and bus 88 to grid of tube 86. As the filter coupler 89 is tuned to pass only the frequency FW this frequency only is received and demodulated by the tube 86 and the modulations reproduced in the output circuit (previously traced) and rendered audible by any suitable type of receiver, not shown, connected in circuit through the jack 112. The receiver may be a simple telephone headset, but is preferably a loud speaker of the usual built-in type as indicated at 116 in Fig. 2 with the necessary amplifying means of any known or other suitable form not shown. Should the subscriber desire to change to a different item he depresses the push button corresponding to the frequency on which that item is being transmitted which releases the push button 97 to disconnect the filter coupler 89, connects in the desired filter coupler and locks itself in actuated position, all in a manner similar to that described in connection with push button 97. To disconnect his receiving set the subscriber simply depresses the "off" button which shifts the locking plate 114 to the left to release whatever button is latched down at the time and locks itself under the release plate. This opens all the contacts thus disconnecting all filter couplers and opening the circuit of the filament current supply at the extreme left hand contacts.

When desired, any of the relay stations may broadcast by radio to enable subscribers to receive therefrom directly by radio, or by wire from a station which receives by radio from the wire relay station. Also, wherever desired, a subscriber's local distributing station may take off the main trunk MT direct. These arrangements are indicated diagrammatically in Fig. 4, where A is the "A" station or primary station, and MT the main distributing trunk distributing to the master B stations B¹, B², B³ and B⁴ each of which is shown with an antenna for radio broadcasting. D⁵ represents one of a group of subscribers' stations which receive over a wire net work from a local distributing station C⁵ receiving by radio from one of the master

B stations, while D⁶ represents one of a group of subscribers' stations receiving over a wire network from a local distributing station C⁶ receiving by wire directly from the main trunk MT. Station BC is a station provided for taking directly from the main trunk and distributing broadcast either to subscribers equipped for radio reception or to local wire distributing stations such as C⁵.

10 In Fig. 5 is shown a master B station here shown as the station B⁴, equipped with apparatus for selective distribution over a common trunk CT to different C stations C¹ and C² serving different groups of subscribers D¹ and D². In the operation of this arrangement, the station B⁴ takes the carrier current of frequency FZ from the main trunk MT through the selective amplifier, tuned to pass only the frequency FZ, and passes it 20 onto the common trunk CT through switch 117 along with the output of one or both of its local transmitters 118 and 119 through switches 120 and 121 respectively, the transmitters 118 and 119 transmitting on frequencies c¹ and c² which are the special receiving frequencies of distributing station C¹ and C² respectively. These three standard frequencies, FZ, c¹ and c² are thus put on the trunk CT common to both C stations.

30 The stations C¹ and C² now both pick off the frequency FZ, intended for both groups of subscribers, by means of their selective relays 122, 123 and distribute it to their subscribers over the networks 124 and 125, respectively, while station C¹ only picks off frequency c¹ and station C² only picks off frequency c² through the special selective relays 126 and 127 respectively. The frequencies c¹ and c² are preferably two of the four standard frequencies other than FZ, for example FW and FX but here designated c¹ and c² because of their being individual to the stations C¹ and C² respectively. As this accounts for only two of the four standard frequencies for 40 each of the groups of subscribers D¹ and D², each of the C stations may supply a third item on the frequency FY by means of local transmitters 128 and 129 respectively, and if desired a fourth item by means of another transmitter at each C station not shown, each arranged to transmit on the frequency special to the other station, this being made possible by virtue of the separation of the networks 124 and 125. Thus each group of subscribers has choice of any one of four items or programs, one of which may or may not be special to its group according to the distribution determined at the station B⁴ which may 50 send different special items to different C stations or the same special item to both. It will also be apparent that the matter received from the main trunk MT on frequency FZ may be made special to one of the 60 C stations by demodulation and retransmis-

sion on one of the special frequencies at station B⁴.

In Fig. 6, is shown a more complete view of the general lay-out of the stations especially the line of descent from the master B stations down, which is the same as that above described for certain B stations, that is, stations B³ and B⁴. This general arrangement however differs slightly from that previously described in that instead of all the master B stations being connected with the primary or A station over a common channel, they are each connected with the primary station over individual trunks T¹, T², etc. The operation of the system as here shown is the same as that of the arrangements previously described except that the primary or A station may transmit items directly to any one of the master B stations on any one or more of a number of frequencies, the master B stations, for example B³ (Fig. 2) passing them on through relay filters to their C stations in a manner as previously described. To show the rotation of the stations previously described in detail, to the general system as illustrated in Fig. 6, they are identified thereon by the same reference numerals, for example (in Fig. 6) station B³, the station C² connected thereto by trunk 50, one of the stations D connected to this station C² and the network 80 connecting C² with its stations D, are the same as the parts designated by the same reference characters in Figs. 1, 2, 3 and 5. It is preferable to provide means for supervision of the subscribers' stations D from their local C stations over individual line connections which may be either individual wire line connections from the local or C station to its D stations as indicated at CTL (Fig. 6) or individual wire lines such as telephone lines TL adapted to be individually connected to the C station through a telephone exchange "TEL. EX." and the C station individual line CL as shown with regard to station C under B² in Fig. 6.

Another arrangement for effecting selective distribution of which the system is capable is shown in the right hand portion of Fig. 6 applied to the arrangement and adjustments of the master station B¹ and the C and D stations thereunder. Here the general relation is the same as that previously described except that the D stations under each C station are divided into two groups by allotment of different receiving frequencies, which gives four groups in all to which the station B¹ may selectively distribute by the use of different combinations of trunks CT¹ and CT² and the standard frequencies FX and FY. For example, the D stations under C¹ are divided into groups D¹ and D² by virtue of their being tuned to receive on the standard frequencies FX and FY, respectively, while the D stations under C² are divided into groups D³ and D⁴ by being tuned to re-

ceive on the standard frequencies FX and FY respectively. Thus in operation, the stations C¹ and C² under B¹ being set to relay the modulated frequencies FX and FY sent them from the B station onto their respective subscribers' networks, the station B¹ may selectively distribute through its C stations to any one of the groups of subscribers by proper trunk and frequency. For example:

10 Frequency FX on trunk CT¹ selects group D¹
 Frequency FY on trunk CT¹ selects group D²
 Frequency FX on trunk CT² selects group D³
 Frequency FY on trunk CT² selects group D⁴

15 In Fig. 7 is shown an arrangement for effecting predetermined distribution or routing by forward frequencies re-routed at the different stages of relay stations. Here the B station for example B³ is arranged to receive items or programs over trunk T³ preferably by carrier current from the primary station, not shown, demodulate the same by the demodulator 130 from which the items may be retransmitted on any one or more of the different standard frequencies FW, FX, FY and FZ through the modulator oscillators or transmitters 131 to 134 respectively, over a trunk 135 to the C station C¹. At C¹, the trunk 135 connects with a pair of filter 20 band repeaters 136 and 137 tuned to pass only the frequencies FW—FX and FY—FZ onto trunks 138 and 139 respectively, leading to different sub C stations. The trunk 139 leads to sub C station C₁¹ where it connects with a 25 pair of filter repeaters 140 and 141 tuned to pass only the frequencies FY and FZ respectively, and arranged with their output currents connected to the lines 142, 143 and 144 as indicated. These stations, especially the 30 stations C² and C₁¹ may conveniently be existing wire distribution service stations such as telephone or telegraph stations, and are here indicated as telephone stations, station C¹ being a main exchange and C₁¹ a branch exchange. At C¹ the line 138 may lead to another branch exchange like C₁¹, or may be a telephone line having two or more party line stations with sets tuned for receiving on one of the standard frequencies FW or FX. At 35 C¹ the lines 142, 143 and 144 represent subscribers' telephone lines.

40 From the above description, it will be clear that in operation, matter received at B³ over the trunk T³ may be routed to any one or more of the ultimate distributing lines 138, 144 or 142—143, or one or both of the two parties or sets of parties on line 138 by use of the proper relay transmitter or transmitter 131 to 134 at B⁴. For example, if 45 it is desired to distribute to the one or more parties on line 138 tuned to FX, the matter is relayed from B³ through transmitter 132, or if to both this set of party line subscribers and the subscriber on line 144 then the matter is relayed through both transmitters 132

50 and 134, transmitting on frequencies FX and FZ respectively. These frequencies may be traced from transmitter 132 and 134, respectively, over trunk 135 to station C¹ where they branch, FX passing through band filter 136 to line 138, while FZ passes through band filter 137 over trunk 139 to station C₁¹ where it is directed to line 144 through filter 141.

55 The arrangement illustrated in Fig. 8 is the same as that of Fig. 7 except that the station C¹¹ instead of serving individual subscribers' lines, serves a network 145 onto which it passes both frequencies FY and FZ, the subscribers' stations D³ and D⁴ being connected in common to the network but divided into two groups by frequencies, the stations D³ being tuned to receive only on frequency FY and the stations D⁴ only on frequency FZ. The operation of the system of Fig. 8 is the same as that of Fig. 7 except that when transmitters 133 and 134 are used at station B³, the matter is routed to one or both of the two large groups of stations on the network 145 according as to whether one or both of these transmitters are operated. By varying the connections or the tuning of the different filters at the different stations, the routing may be varied to suit different requirements.

60 In Fig. 9, is shown an arrangement of the B, C and D stations for selective distribution through a C station to D stations on forward frequencies over a common medium, here shown as a common wire network. Here the relation of the primary or A station and the master B stations are the same as that of Figs. 1 and 2. From the master B stations on down to the D stations, the present arrangement differs from that of Figs. 1 and 2 in that the master B station, for example, B¹, is connected with its C stations C¹ and C² over the same common network 146 to which the D stations are connected. Here the arrows marked b, c and d represent the receiving frequencies of the stations B, C and D, respectively, and their direction of distribution, it being remembered of course that the carrier currents are not unidirectional, the arrows being used simply to show direction of distribution or routing only. Station B¹ is tuned to receive from the primary station on frequency b and retransmit over the network 146 on frequency c while station C¹ receives from the network on frequency c and transmits over the same network on frequency d to which the subscribers' stations D² are tuned for reception from the same common network. Other C stations and their D stations such as C² and its D stations D² are also connected to the same common network 146 but tuned to a different set of frequencies. Thus, in operation, when B¹ transmits on frequency c over the network, the signals will be dis-

tributed through C¹ to its D stations D¹, to the exclusion of stations C² and D² on the same common network. Similarly, the same or different signals may be distributed 5 through C² to stations D² to the exclusion of the first set of stations. The station TC represents a telephone exchange central office having access to the several B, C and D stations through individual wires such as 147 10 and 148 indicated in dotted lines. Through these connections the C station may have access to the D stations for supervision, pick up of items to be broadcasted, etc. It is also possible for the station C² to pick up from 15 one of the stations D² by the use of a portable wire transmitter at the particular D² station arranged to transmit on the frequency c to which the receiving apparatus at C² is tuned.

20 In Fig. 10, is shown a scheme of distribution in which the four time divisions of the country are served with overlapping repetitions of the same program which may be made up of national items exclusively. The 25 four divisions are allotted receiving frequencies FW, FX, FY and FZ but the maximum number of frequencies required at any one time is three, and when all four divisions are receiving, only two frequencies are 30 required for the stated program. The value of this arrangement lies in the fact that two frequencies and at the same time three out of the four are available for "specials" which may originate at A, B or C stations. It will 35 be observed that frequency FW for division 1 carries the program straight through from 6 p. m. to midnight, from item 1 to item 18 inclusive, in regular numerical order. Frequency FX intended for division 2 commences an hour later and carries the same 40 program straight through if desired, but preferably does not carry items 7 to 15 inclusive because those items can be obtained during the same period from frequency FX for "specials", or saving it entirely. Frequency 45 FY commences an hour later than FX and can also carry straight through but preferably has items 4 to 12 inclusive omitted for the same reasons as before stated with respect to FX. Frequency FZ commences an 50 hour later than FY, and carries straight through the entire program. In order that divisions 2 and 3 may be able to receive all national program items, their receivers are 55 tunable to frequencies FW and FZ as well as their own. Division 2 would first receive on frequency FX the first six items, then tune to frequency FW for items 10 to 15 inclusive, then tune to FZ for items 7, 8 and 9, and finally tune back to its own frequency for 60 the last three items in the program. To indicate this routing on selection by means of frequencies, I have shown dotted lines indicating the items and the frequencies received 65 in divisions 2 and 3 according to this method.

The exes shown in the figure indicate that the particular frequency opposite which they appear does not carry the items under which they stand but is blank and available for "specials" or the like. Of course, the hours, 70 the number of items, and other conditions are arbitrarily assumed and may be varied without departing from the invention. Attention is also called to the fact that while I speak of tuning, it is not essential to have 75 tunable instruments or to actually change the tuning during receiving, as each division may have a plurality of receivers fixedly tuned which can be switched in when required or left in and the relay circuits switched to one 80 or another as required.

What I claim is:

1. In an organized wired broadcasting system, a plurality of subscribers' stations divided into local groups, a centralized local 85 distributing station for each group, a wired network connecting said subscribers' stations and their respective local distributing stations, wired broadcast receiving means at each subscriber's station connected with its 90 associated local station for supervision therefrom, a district service station connected to a group of said local distributing stations over a common wire connection, wired broadcast receiving means at each local distributing 95 station the receiving sets of different local distributing stations being tuned to different wave lengths different for different stations, means at said local distributing stations for relaying signals received on their 100 receiving sets to their respective subscribers over the connecting network, and means at the district station for transmitting the same or different signals over said common wire 105 connections on the said different wave lengths to which the receivers of said local distributing stations are tuned whereby the local distributing stations and their groups of subscribers are segregated by wave lengths independently of physical connections. 110

2. In an organized wired broadcast system, a plurality of wired networks each having a plurality of subscribers' stations connected thereto in common, the subscribers on a common network being divided into groups 115 by tuning, carrier current receiving means at each subscriber's station connected for reception from its network, the receiving sets of the different groups on a network being tuned to different given wave lengths different for different groups, a local distributing station, a district distributing station, said local distributing stations being each connected to one of said different wired networks, wire connection between said district distributing station and all said local distributing stations, means at said district station for transmitting signals to the local distributing stations on said different given 120 wave lengths, and means at the local stations 125

for relaying certain of said wave lengths onto the different networks whereby a signal may be routed from said district station to any group of subscribers on any of said networks.

3. An organized system of wire communication having subscribers' stations distributed over a wide area, local exchange stations serving said subscribers in local aggregated groups, said local exchange stations each connected to its subscribers by individual wire circuits, and all said local exchange stations interconnected over the general area by wired trunk circuits, in combination with subscribers' carrier current receiving stations distributed over the same area arranged in groups, each group connected to receive from a local network and connected with the same subscribers' line circuits, local central stations arranged to broadcast by carrier current on said networks and containing terminals of said lines, and also terminals of said wired trunk lines, and an organized system of carrier current relaying comprising graduated stages of relay stations arranged to cover the general area, one stage being the local stations distributing direct to the subscribers by carrier current over the local networks on fixed wave lengths, and supervising the subscribers' receiving over their individual wire circuits, the next being an intermediate stage receiving over a trunk on a fixed wave frequency and distributing to the local stations over a trunk on a second fixed wave frequency, and so on to a master station broadcasting for the time being, over a trunk to one or more relay stations on carrier currents of different frequency.

4. An organized system of carrier current broadcast distribution, comprising a large number of subscribers divided into groups with a common network for each group from local distributing central stations, wire connections other than said networks from each of said local central stations to its subscribers, means at the local central stations for broadcasting by carrier current on a fixed carrier wave frequency to subscribers in their respective networks, and a plurality of sets or stages of radio relay stations each set or stage receiving on the same carrier wave length and relaying the modulation on a different carrier wave length fixed for any particular station of the stage next below it.

5. In an organized wired signal system having a plurality of subscribers' stations divided into groups with a subscriber's distributing service station for each group, a common wire network connecting each group and its service station, carrier current receiving means at each subscriber's station having its input circuit means connecting it to said network and connected with its associated service station for supervision therefrom, trunk lines connected to said service

stations, and means for transmitting different classes of matter over different trunks to the different service stations to effect differential distribution among said different groups of subscribers.

6. In a system of broadcasting, a wire circuit, means for transmitting signal modulated carrier currents over said circuit, a relay station containing an amplifying relay selective for one of said currents, local distributing stations connected to said relay station by a wire circuit, each containing a selective amplifier and relay for said carrier current, and subscribers' stations connected to each of said distributing stations, each of said distributing stations having a second amplifying relay selective for a second carrier current frequency allotted to it, and means at the relay station to distribute signals to said distributing stations by sending to one or the other over the common circuit each on its own allotted frequency.

In testimony whereof I hereunto affix my signature.
